UNITED STATES PATENT OFFICE

CHARLES H. COLTON, OF CHICAGO, ILLINOIS, ASSIGNOR TO GREAT LAKES DREDGE & DOCK COMPANY, OF CHICAGO, ILLINOIS, A CORPORATION OF NEW JERSEY

DREDGE DISCHARGE CONDUIT

Application filed December 23, 1931. Serial No. 582,798.

This invention relates to improvements in dredge discharge conduit and its purpose is to provide means by which the location and character of the discharge of pipe lines from dredges may be regulated and controlled. It is common practice to employ pipe lines of varying lengths leading from dredges for conveying sand or other sediment held in suspension in water which is pumped from the bottom of a river, lake or harbor and deposited at the end of the pipe line for the purpose of filling in a portion of a basin or river bed and thereby extending the shore line. When the material is discharged from the pipe line leading from the dredge, the sand or other sediment gradually accumulates and the water with which it was intermingled during the dredging and conveying process, runs off. Heretofore, such pipe lines from dredges have not been provided with adequate or efficient means for effecting the discharge from the pipe lines at various points along their length and the means for effecting discharge at the end of the pipe line has produced undesirable results in that the discharge current ordinarily tends to excavate a large hole at the mouth of the pipe, making it difficult to move the mouth of the pipe to a new location and leaving a depression which must be filled up by hand labor after the dredging operation is completed.

The principal object of the present invention is to provide a dredge discharge conduit or pipe made up of one or more sections provided with improved openings in their sides so that a portion of the stream passing through the conduit may be discharged at any desired point along the length of the conduit leading from the dredge. Still another object of the invention is to provide an improved dredge discharge conduit made up of one or more sections provided with improved trap doors capable of deflecting portions of the current passing through the conduit laterally through discharge openings, while permitting the remainder of the current to pass along to the end of the conduit. A further object of the invention is to provide an improved dredge discharge conduit provided with a lateral opening having a de-

flecting member extending inwardly therefrom to intercept and deflect a portion of the current passing through the conduit. A further object of the invention is to provide an improved diffuser or discharge nozzle for use at the discharge end of the conduit for effecting the discharge of the conveyed material without effecting any undesirable excavation of the earth adjacent the mouth of the conduit. Still another object of the invention is to provide a dredge discharge conduit having an adjustable trap door which may be regulated to effect a discharge of greater or lesser quantities of material at any desired point along the length of the conduit. Other objects relate to various features of construction and arrangement which will appear more fully hereinafter.

The nature of the invention will be understood from the following specification taken with the accompanying drawings in which one embodiment of the invention is illustrated. In the drawings,—

Fig. 1 shows a side elevation of a portion of the dredge discharge conduit mounted on the usual stilts or horses and provided with the improvements of the present invention;

Fig. 2 shows a transverse section taken on the line 2—2 of Fig. 1;

Fig. 3 shows an enlarged top plan view of a portion of the conduit illustrated in Fig. 1, including the discharge end thereof;

Fig. 4 shows a side elevation of the portion of the discharge conduit illustrated in Fig. 3;

Fig. 5 is an enlarged transverse section through the nozzle section or diffuser taken on the lines 5—5 of Fig. 4;

Fig. 6 is a transverse section through the nozzle section or diffuser taken on the line 6—6 of Fig. 4;

Fig. 7 is a transverse section through the nozzle section or diffuser taken on the line 7—7 of Fig. 4;

Fig. 8 shows a side elevation of one of the trap doors mounted in the wall of the discharge conduit;

Fig. 9 shows a longitudinal section taken on the line 9—9 of Fig. 8; and

Fig. 10 shows a transverse section taken on the line 10—10 of Fig. 9.

In the drawings, the improved dredge discharge conduit 15 comprises a number of similar connected sections 15^a and an end section or diffuser 15^b which serves as a discharge nozzle. The sections of the pipe or conduit are supported upon stilts or horses 16 comprising bars 17 which are pivotally connected at an intermediate point 18 and spaced apart below the pivotal point by a crossbar 19. These horses 16 rest upon the surface of the earth or other support and the upwardly diverging arms thereof serve to support the conduit 15 so that it may have the desired elevation for conveying the more or less fluid contents thereof to the place of discharge. The ends of the conduit sections have rings 21 welded thereon and the end of one section 20 is adapted to fit within the ring of the next adjacent section so that they have a slight telescoping engagement with each other while at the same time maintaining a tight joint. The ends of the conduit sections are 25 clamped together by fastening means comprising lugs 22 which are welded onto the ends of one section and connected by chains 23 with other lugs 24 which are welded upon the end of the next adjacent section. Each 30 chain 23 is preferably connected to a bolt 25 which extends through an aperture in the lug 24 and is engaged on its threaded end by a nut 26 so that, upon tightening these nuts, the chains 23 are drawn taut and the contacting ends of two adjacent conduit sections are 35 firmly clamped together. This method of fastening is employed for uniting the adjacent sections 15^a and also for the purpose of connecting the last section 15^a with the diffuser or nozzle section 15^b.

The conduit sections are preferably made of steel tubing adapted to withstand the abrasive effects of the materials being conveyed therethrough and the end section or 45 nozzle 15^b is open at its outer end as shown at 29 so that a considerable portion of the materials conveyed through the conduit is discharged at this point. In order to minimize the discharge at the end of the conduit and to effect a more or less general diffusion of the materials conveyed at the end of the conduit, the end or nozzle section 15^b is provided with a number of lateral discharge 50 openings 30 which are formed by cutting out sections of the steel tubing along three sides of a rectangle and then bending the intervening metal inwardly to form an inclined vane or tongue 31. In the embodiment illustrated, there are nine openings 30 and nine corresponding vanes 31 in the section 15^b and these are distributed so that they become progressively more numerous as the mouth 29 of the conduit is approached. The openings and vanes are also preferably distributed, as 55 shown in the drawings, so that, toward the

inner end of the nozzle section, the openings are located chiefly or entirely on the upper side of the conduit, with a gradual extension of the openings toward the lower side of the conduit as the discharge opening 29 is approached. The vanes 31 are inclined inwardly toward the axis of the conduit and away from the discharge opening 29 so that they form inclined deflecting members adapted to intercept and deflect outwardly portions of the current passing through the tube. The outer portions of the current which are thus deflected cause jets or sprays of the water and sediment to be discharged laterally from the nozzle section 15^b with the result that there is a general diffusion and discharge of the material around the mouth of the conduit with no heavy current being discharged continually at one point, thus avoiding the erosion and excavation of the earth beneath the mouth of the conduit, such as has heretofore resulted from the discharge of such materials from the pipe lines of dredges. The vanes 31 are curved in transverse cross section to correspond with the curvature of the conduit from which they have been cut, and the thickness and stiffness of the wall of the conduit is such that the joint between each vane and the conduit along a line 32 is sufficient to hold the vane in the desired position notwithstanding the impact of the current passing through the conduit. Other desired arrangements of the openings 30 may be employed, but the openings may preferably be distributed so that the discharge takes place largely from the upper and lateral sides of the conduit in order to decrease the eroding effect of the discharge upon the underlying earth.

In order to effect some discharge of material at various points along the length of the conduit 15 and through the walls of the sections 15^a thereof, the sections 15^a are provided with lateral discharge openings 34 which may be wholly or partially closed by trap doors 35 mounted in frames or supporting plates 36 which are bolted or otherwise secured to the walls of the conduit sections, preferably on the lateral sides thereof, as the apparatus is shown in Fig. 1, so that the discharge through these openings takes place laterally from the conduit, rather than downwardly. The plates 36 have a transverse curvature corresponding to that of the outer surface of the conduit, as shown in Fig. 10, and each plate or frame is provided with an inwardly extending boss or flange 36^a around the opening 34 therein, to fit within the larger rectangular opening 37 which is cut in the wall of the conduit. When thus seated in place, the plate or frame 36 is secured to the conduit by a series of bolts or rivets 38. The opening 34 may be normally closed by the trap door 35 which is in the form of a plate having a slight transverse curvature to cor-

respond with that of the conduit and adapted to fit within the openings 34 in such a manner that when it is closed, the inner surface thereof lies substantially flush with the inner surface of the conduit. At one end, each door 35 is provided with an upwardly or outwardly extending transverse boss 39 having a pin 40 passing therethrough and pivotally engaging the ears 41 which are formed integrally with and arranged to extend outwardly from the plate or frame 36.

Each trap door 35 is so mounted that it is adapted to swing downwardly or inwardly toward the axis of the conduit to assume a position inclined away from the discharge end of the conduit, so that it is adapted to intercept and deflect outwardly a portion of the current passing through the conduit. For this purpose the inner surface of the door is 20 tapered or curved outwardly at one end as shown at 35^a and the adjacent transverse edge of the opening 34 is similarly inclined or beveled as shown at 36^b so that this swinging movement may be permitted while at the same time securing a substantially tight closure when the door is in a closed position. Each door 35 is adapted to be held in the desired inclined position with respect to the wall of the conduit by means of a link 44 30 which is pivotally connected at its inner end to a pair of ears 45 extending outwardly from the surface of the door 35 to receive the end of the link between them. A pivotal connection between the ears and the link is established by means of a rivet 46. The link extends outwardly from the door 35 and passes between a pair of arms or ears 47 which are formed integrally with the plate 36 and which extend outwardly and inwardly over 40 the opening 34. The outer ends of these ears are provided with apertures 48 and the link 44 is provided throughout its length with a series of spaced apertures 49, any one of which may be caused to register with the apertures 48 so that a pin 50 may be passed through the aligning apertures to hold the link 44 in adjusting position. The pin 50 is preferably carried at the end of a chain 51 which is welded to the plate or frame 36 as 50 shown at 52. By the use of the detachable pin 50, the effective length of the link 44 may be varied to secure the desired inclination of the door 35 carried by any frame 36. This adjustment permits the effective opening of 55 any frame 36 to be varied in order to secure the desired degree of discharge at any point along the length of the conduit. In the accompanying drawings, two frames 36 and two corresponding discharge openings 34 are 60 shown along the side of each conduit to discharge in a lateral or horizontal direction, but any other desired arrangement of the discharge openings may be employed and their number may be varied as desired to suit the 65 requirements of the particular job being done.

An important feature of this improvement is that it may be applied to any conduit section very readily by cutting a hole in the conduit and then applying the frame 36 by means of bolts or the like. By distributing the trap doors along a considerable length of the discharge conduit 15, the discharge of the sediment may be regulated and made to be more or less uniform over a relatively large area instead of effecting a rapid accumulation of material at the mouth of the conduit which requires the frequent extension of the conduit or the frequent removal of the discharge end thereof to a new location.

Although one form of the invention, including one form of trap door and one form of diffuser or discharge nozzle, has been shown or described by way of illustration, it will be understood that the invention may be constructed in various other embodiments within the scope of the appended claims.

I claim:

1. A dredge discharge conduit provided at its discharge extremity with a nozzle section having a plurality of closely spaced openings in its annular wall to cause the contents of the conduit to be discharged in a spray over a relatively large area.

2. A dredge discharge conduit having a discharge opening in its lateral side and a deflecting vane extending inwardly from said opening.

3. A dredge discharge conduit having a discharge opening in its lateral side, a deflecting vane extending inwardly from said opening, and means for changing the inclination of said vane.

4. A dredge discharge conduit having an opening in the side thereof, and a vane inclined inwardly from one edge of said opening toward the current passing through said conduit.

5. A dredge discharge conduit having an opening in the side thereof, and a deflecting vane having one edge thereof attached to said conduit at the side of said opening nearer the discharge end of said conduit and inclined inwardly toward the current passing therethrough.

6. A dredge discharge conduit provided at its discharge extremity with a nozzle section having a plurality of openings distributed over the lateral sides and top portion thereof whereby the contents of the conduit are discharged upwardly and laterally at the end of the conduit.

7. A dredge discharge conduit having a plurality of openings in the wall thereof adjacent its discharge end, said openings increasing in number as the end of the conduit is approached.

8. A dredge discharge conduit having a plurality of openings in the wall thereof adjacent its discharge end, said openings in-

creasing in number as the end of the conduit is approached, and vanes inclined inwardly from said openings and away from the discharge end of the conduit.

9. A dredge discharge conduit having a terminal section provided with an opening in its lateral wall formed by cutting out a portion of the metal along three right angular sides and then bending the intervening metal inwardly to form an inclined vane directed away from the discharge end of the conduit.

10. A dredge discharge conduit comprising a terminal section open at its discharge end and having a plurality of diffusing openings in the wall thereof with vanes inclined inwardly from said openings at the edges thereof adjacent the mouth of the conduit.

11. A dredge discharge conduit comprising a pipe section having an opening in the side thereof, and a gate hinged at one edge of said opening and inclined inwardly therefrom to deflect the contents of said conduit outwardly through said opening.

12. A dredge discharge conduit comprising a pipe section having an opening in its side, a gate hinged along that edge of said opening which is nearer the discharge end of said section, and means for adjusting the inclination of said gate and securing it in adjusted position.

13. A dredge discharge conduit comprising a pipe section having an opening in the wall thereof, a gate hinged at one edge of said opening, a perforated link connected to said gate, and means cooperating with the perforations in said link for securing said gate in adjusted position.

14. The combination in a dredge discharge conduit of a pipe section having an opening in the wall thereof, a frame secured around said opening, lugs projecting from said frame, a gate pivoted between said lugs and adapted normally to close said opening, and means including a link for securing said gate in closed position and for adjusting said gate to the desired open position inclined inwardly from the wall of said conduit.

15. The combination in a dredge discharge conduit of a pipe section having an opening in the wall thereof, a frame detachably secured to said conduit and having an opening therethrough with a flange extending inwardly around said opening to engage the walls of said first named opening in said conduit, a gate mounted within the opening in said frame, and adjustable means for securing said gate in position inclined inwardly from the wall of said conduit to deflect outwardly a portion of the contents passing through said conduit.

16. A dredge discharge conduit provided at its discharge extremity with a plurality of closely spaced openings in its annular wall, and vanes extending inwardly from the edges

of said openings to deflect the contents of said conduit through said openings.

In testimony whereof, I have subscribed my name.
